UNITED STATES PATENT OFFICE.

JOSEPH C. STRICKLAND, OF CLEARFIELD, PENNSYLVANIA.

GARMENT-SUPPORTER.

SPECIFICATION forming part of Letters Patent No. 717,722, dated January 6, 1903.

Application filed January 30, 1902. Serial No. 91,914. (No model.)

To all whom it may concern:

Be it known that I, JOSEPH C. STRICKLAND, a citizen of the United States, residing at Clearfield, in the county of Clearfield and State of Pennsylvania, have invented certain new and useful Improvements in Garment-Supporters; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in clasps or garment-supporting devices which are adapted to be clamped to the upper edge of a garment, thus dispensing with buttons and providing a means for 20 supporting trousers, &c., which may be easily and quickly adjusted to the garment and removed therefrom.

The invention relates, further, in connection 25 with the clamping-jaws adapted to engage the garment, of means for locking the jaws in clamping positions and for holding the jaws locked to the garment by a detachable strap, which is adapted to be held to a pair of suspenders.

30 More specifically, the invention consists in the provision of two jaws which are pivoted together, one end of one jaw being bent to form a spring adapted to bear against the other jaw to hold the jaws open when a locking device is released, and in the provision 35 of a ring or loop which draws the spring-actuated jaw into a clamping position as said ring or loop is drawn into a position to engage in a hooked end of the spring-pressed jaw, thus 40 securely holding the jaws in clamping positions.

The invention will be hereinafter more fully described, and specifically defined in the appended claims, and is clearly illustrated in 45 the accompanying drawings, which, with the letters of reference marked thereon, form a part of this application, and in which drawings similar letters of reference indicate like parts in the several views, in which—

50 Figure 1 is a perspective view of my invention shown as applied to the edge of a garment, the latter being shown in dotted out-

line. Fig. 2 is a vertical central sectional view of the device, showing the jaws open. Fig. 3 is a vertical central sectional view 55 showing the jaws held together or in a locked relation. Fig. 4 is a detail view in perspective of one of the jaws. Fig. 5 is a detail view of the other jaw.

Reference now being had to the details of the drawings by letter, A designates one of the clamping-jaws, made, preferably, of flexible metal and having a series of upset spurs A' on its inner face to provide a secure hold on the garment to which the jaw is to be 60 clamped. The upper end of said jaw is preferably recessed, forming two flexible arms B and C, which are of substantially inverted-U shape, and which have their ends curved outward from the face of the jaw, as at B' and 70 C', respectively. Ears D are formed on the edges of said jaw A, which are apertured to receive a pin E, on which the ears F are pivotally mounted. Said ears F are formed on the edges of the jaw H, which jaw is provided with upset 75 spurs H' on its inner face, as shown, and has its upper portion contracted, as at K, with its extreme upper end bent to form a hook K', in which hook the ring or loop N is designed to 80 engage when the two jaws are held in clamping positions, in which positions said ring or loop N engages the hooked end K' of jaw H as well as the bent or hook-shaped portions 85 of the flexible arms B and C, as clearly shown in Fig. 1 of the drawings. The cover-plate H² 90 has three edges h bent over the edges of the jaw H and is held to the latter. It will be observed that when the two jaws are pivotally mounted on the pin E the outwardly-curved portion M, which connects the arms B and C, 95 is held against the inner face of the contracted portion K of the jaw H, as shown in Figs. 2 and 3, and normally in the position shown in Fig. 2 hold the jaws open. When the loop N, which is passed underneath the contracted portion K of jaw H and the arms B and C, is pulled toward the hook K' and the bent portions of arms B and C, the two jaws will be thrown toward each other. After the loop N passes by the bulging portion and enters the hooked 100 end K' the bulging portion will spring toward the inner face of the jaw A and serve to lock the loop in the position shown in Figs. 1 and 3. A strap P is designed to be passed

through said loop and, provided with an ordinary glove-fastener, may be locked to the loop, as shown. This strap is adapted to be fastened to an ordinary pair of suspenders, 5 and all that is necessary when it is desired to detach the suspenders from the loop is to unfasten the glove-fasteners and allow the end of the strap to pass through the loop, the latter and the clamping-jaws being prefer-
10 ably left connected to the garment. If desired, the clamp members may be detached from the garment by simply pushing the loop down over the bulging portion into the position shown in Fig. 2 of the drawings, in which case 15 it would not be necessary to detach the strap, as the clamping members could be removed with the suspenders.

From the foregoing it will be observed that I produce a simple and inexpensive device 20 as a substitute for buttons and to which suspenders may be easily connected and disconnected, and the clamping-jaws may be quickly and easily applied and adjusted at different locations to the edge of a garment.

25 Having thus described my invention, what I claim to be new, and desire to secure by Letters Patent, is—

1. A garment-supporter, comprising two

clamping-jaws pivoted together, one of said jaws being bent at one end and bearing yield- 30 ingly against the inner side of the other jaw, and adapted to hold the jaws in open relation, a loop engaging bent portions of the jaws and adapted to draw the two clamping-jaws together and hold same in locked clamp- 35 ing positions, as set forth.

2. A garment-supporting device, comprising two clamping-jaws A and H, pivoted together, said jaw H having a contracted portion, the end of which is bent to form a hook, 40 one of said jaws having a recessed portion with flexible arms bent upon themselves, with their outwardly-bent ends held yield- 45 ingly against the inner face of the second jaw, a loop passed under the bent arms B and C of jaw A and the contracted portion K of jaw H and adapted to draw the clamping-jaws together and hold same in locked relations, as set forth.

In testimony whereof I hereunto affix my 50 signature in presence of two witnesses.

JOSEPH C. STRICKLAND.
